UNITED STATES PATENT OFFICE.

HARRY H. IDE, OF CHICAGO, ILLINOIS, ASSIGNOR TO KELLOGG SWITCHBOARD & SUPPLY COMPANY, OF CHICAGO, ILLINOIS, A CORPORATION OF ILLINOIS.

AUTOMATIC TELEPHONE SYSTEM.

1,194,741.

Specification of Letters Patent. Patented Aug. 15, 1916.

Application filed June 19, 1914. Serial No. 846,018.

To all whom it may concern:

Be it known that I, HARRY H. IDE, a citizen of the United States of America, residing at Chicago, in the county of Cook and State of Illinois, have invented certain new and useful Improvements in Automatic Telephone Systems, of which the following is a specification.

My invention relates to automatic telephone exchange systems and has for its object the provision of an improved system of this character in which the control of the various operations incident to the completion of a call are controlled principally by differential relays.

My invention further contemplates to so arrange the relays and other local apparatus at the exchange as to provide a clear talking circuit.

My invention also has for its object the provision of a two wire circuit simplified in a number of operating and control mechanisms required to complete the various functions required to be performed incident to the operative actuation of the various devices.

An important feature of my invention concerns itself also primarily with preventing the called subscriber from holding up the entire connection in case the calling subscriber hangs up but the called subscriber does not.

I will explain a system embodying my invention more in detail by referring to the accompanying drawings illustrating the same in which—

Figure 1 Part I and Fig. 1 Part II represent diagrammatically a system including a line switch, first selector, and connector arranged in accordance with my invention together with their association with subscribers' lines to complete a call; Fig. 2 is a diagrammatic view showing the mechanical arrangement of the line switch; and Fig. 3 is a semi-diagrammatic view showing the mechanical arrangement of the selector and connector.

In order to facilitate a proper understanding of the drawing it is pointed out that Fig. 1 Part II is adapted to be a continuation to the right of the circuit shown in Fig. 1 Part I. It may also be pointed out that features of the line switch and selector are more clearly set forth in application of William Kaisling, Serial No. 600,664,

filed Jan. 3, 1911, and the application of Charles S. Winston, Serial No. 749,324, filed Feb. 19, 1913.

I have shown the subscriber's substation at A as including the usual talking equipment of a common battery telephone with the addition of a calling switch 1 adapted to break the continuity of the circuit preferably of the line conductor 2, and a second line conductor 3 completing the extension of the subscriber's equipment to the central exchange where it terminates in a line switch B. The circuit for the subscriber's station A will be carried through a series of continuations to finally establish a connection with the subscriber's telephone C which is also shown as having a line switch D similar to the line switch B. The line switch B, for instance, is provided with wipers 4, 5 and 6 diagrammatically indicated by the wiper 4 in Fig. 2, which wipers are controlled by the motor magnet MM, the line relay LR and the cut off relay CO. The line relay and cut off relay both control holding pawls for the step-up element which actuates the wipers and the motor magnet controls the step-up pawl to move said wipers. An off normal switching device ON is provided which is actuated with each first step of the wipers. The selector and connector switches in mechanical arrangement are like the structure of Fig. 3 where the wipers 7, 8 and 9, diagrammatically indicated at 7 in Fig. 3, are controlled by a rotatable spindle 10 rotated by the primary magnet PM and also controlled in a vertical movement by the secondary magnet SM which controls the driving bar 11. The wipers 7, 8 and 9 are adapted to engage successive series of contacts arranged in what might be called vertical and horizontal rows as more clearly seen from Fig. 3, the complete movement of the wipers being indicated by the dotted line 12 when traveling from the zero position shown in Fig. 3 back to this zero position after having completed a contact. Each set of contacts is three in number to correspond respectively to the wipers 7, 8 and 9 as will be readily apparent. The selector switch also controls a plurality of sets of off-normal contacts, the primary off normal contacts PON and the secondary off-normal contacts SON, each of which is actuated with the first movement respectively in a rotary and in a vertical di-

rection. When I say 'vertical direction', I wish it understood of course that the upward movement of the wipers is not in a straight line, but is along the arc of a circle as these wipers are pivoted.

Assuming now for instance that a call is to be traced from the substation A to the substation C, upon the removal of the receiver at the substation A, line relay LR is energized which closes a circuit from the ground through the closed contact on the off normal switch ON to the cut off relay CO. At the same time a ground from 13 is placed upon two of the armatures of the cutting out relay CO due to the attraction of the two upper armatures of the relay LR. The cut-off relay CO thereupon closes a circuit through the magnet MM, and the intermittent source of current terminating at 20 the ground 13, whereupon this motor magnet actuates the wipers 4, 5 and 6 to select a non-busy first selector. The very first movement of the wipers of course transfers the off normal contact to its alternative position. 25 The transference of this off normal contact opens the circuit through the cut-off relay, but this cut-off relay is maintained energized so long as the wiper 4 finds a grounded contact, thereby keeping the circuit through 30 the motor magnet MM closed. When an idle selector is reached, the cut-off relay CO is deenergized and opens the circuit of the motor magnet. The line relay LR is slow acting and holds momentarily even though 35 the cut-off relay releases until this line relay again finds its circuit closed as will now appear. As soon as the wipers 5 and 6 reach the terminals of the line conductors 14 and 15 of the first selector, impulse relay IR is 40 energized as is readily apparent by being connected to both of these conductors 14 and 15, the circuit through which conductors are closed by way of the subscriber's station A. The impulse relay IR thus attracts its armatures, thereby placing a ground from 45 16 through its armature 17, upon the contact 19 leading to the release relay RR which is thereupon energized and locks itself in position through its own grounded armature 50 18. At the same time secondary release relay SR receives current through both of its windings as will be clear, but being differentially wound, does not actuate its armature. Similarly a circuit may be traced from 55 ground at 20 through the armature of the release relay RR, the normal contact of the primary off-normal switch PON, the private conductor 21, through the wiper 4, through the line relay LR, through battery to ground, thus keeping this line relay energized. The subscriber then actuates the switch 1 a given number of impulses corresponding to one of the digits of the number called for, whereupon the impulse relay IR 60 has its circuit broken and made a number

of times corresponding to the digit. The release of the armature 22 periodically grounds the primary magnet PM at 18, relay RR remaining energized, to thereby step the wipers 7, 8 and 9 to the proper vertical bank corresponding to the desired second selector or connector. During this interval the secondary release relay SR has had the circuit through one of its windings periodically made and broken at the armature 22, thereby destroying the balance of the two windings and causing this relay SR to attract its armature 23 and to keep it attracted as the time between impulses is not sufficient to again restore the balance sufficiently to allow this armature to retract. For the same reason relay RR remains energized. Upon completion of the impulses the relay IR of course remains again energized, whereupon the balance is restored as far as the relay SR is concerned to again permit retraction of the armature 23, thereupon closing a circuit from the ground of the primary off normal switch PON (which is now in its alternative position) through the normal contact of the secondary off-normal switch SON, through the test relay T, through battery to ground. A circuit is thereupon established through the secondary magnet SM and its associated source of alternating or intermittent current to ground at 16, whereupon the wipers 7, 8 and 9 are carried in a vertically disposed arc over a series of contacts leading to a particular set of connector switches, which movement continues so long as the wiper 7 finds a grounded contact 24, but which ceases when this wiper has found an ungrounded contact such as the one associated with the private conductor 25. Of course the first movement toward the selection of an idle connector in the desired group causes a movement of the secondary off normal switch SON to its alternative position, thereby breaking the originally established circuit through the test relay T. However the relay T is maintained in an energized condition so long as the wiper 7 finds a grounded contact 24 as a circuit can be traced from the ground at 26 through the test relay T, the armature 27 of the relay RR, the front contact of the armature 28 of the relay T, armature 28, wiper 7 to the grounded contact 24. As soon as the wiper 7 reaches an ungrounded contact relay T is deenergized, thereby deenergizing the secondary magnet SM to prevent further movement of the wipers 7, 8 and 9. The wipers 8 and 9 are now assumed to be in association with the line wires 29 and 30 of either a second selector or connector, a connector being herein shown and at the same time the wiper 7 is associated with the conductor 25, which conductor 25 immediately becomes grounded at the connector as will 130

appear from the subsequent description, whereupon the circuit through the main release relay MRR is closed, and remains closed, this circuit being traced from the ground, through battery, through the relay MRR, armature 28 of the relay T, through the wiper 7 to the subsequently to become grounded private conductor 25. The circuit has thus been established to an idle 10 connector.

The energization of the magnet MRR disconnects the impulse relay IR from the talking strands 14 and 15, whereupon a balance is established through the windings of the 15 relay RR so that this relay releases, whereupon the relay SR also releases, the relay T having already been released as stated. The energization of the relay MRR also opens the release circuit at the armature 31. The 20 line switch of the calling line is thus held up as the line relay of the line switch has its circuit completed through the ground of the primary off normal switch PON, of the first selector, and the first selector would be 25 held up by the primary off normal switch of the second selector if such were used, after the second selector had made its operations, the relay MRR of the first selector prior to the movement of the primary off normal 30 switch PON of the second selector having its circuit closed through the agency of the release relay of the second selector. All this it is thought will be readily clear and it will be only necessary for me to describe the 35 connector operation. The subscriber's circuit is thus completed through to the talking conductors 29 and 30 of the connector E which forms Part II of Fig. 1. The subscriber's circuit being closed, the completion 40 of the circuit to these conductors 29 and 30 causes the operation of the relay IR'. The operation of this relay grounds the private conductor 25 by way of the armature 32, thus establishing the circuit before mentioned through the relay MRR of the first selector or a similar relay if a second selector happens to be interposed. The operation 45 of the relay IR' also closes a circuit from the ground through the armature 32, conductor 33, back contact of the primary off normal switch PON', through a winding of the relay RR', through battery to ground. This relay is thereby energized and locks 50 itself through its left hand winding, the right hand winding being open at the armature 32. The operation of the relay RR' connects ground by way of the armature 34 to a terminal of the lower winding of the relay RI. A connection is also established 55 between the right hand winding of the relay RR' by way of the armature 35, armature 36, to the open back contact of the armature 32 of the relay IR'. The operation of the relay RR' also at the armature 37 opens the 60 circuit from the secondary magnet SM' to

the interrupter contact of the primary off normal switch PON'. The operation also closes circuit through the relay M which however does not operate as it is wound differentially, the circuit through one of the 70 windings of this relay M being closed at the armature 34 and the other at the armature 38. The subscriber now sends the impulses which are to cause the primary movement of the connector. The impulse relay IR' operates at each impulse, the first impulse moving the primary off normal switch PON' to its alternative position, whereby a common ground is provided for the connector through the switch arm 39 and also the 75 switch arm 40.

The first impulse opens the circuit through the left hand winding of the relay M at the armature 41, thereby actuating this relay M. The relay M thereupon attracts all of its armatures and being differentially wound remains actuated throughout these primary impulses, but releases its armatures after cessation of the impulses. Similarly the 80 actuations of the armature 32 breaking the 85 circuit through the right hand winding of the relay RR' do not cause deenergization of this relay. The intermittent operation of the armature 41 establishes a circuit from ground at 42 through switch contact 40, 90 conductor 33, armature 41, armature 43 of relay M, by way of armature 44 through the primary magnet PM' to ground. The requisite number of impulses being sent, the connector is stepped around to the right 95 100 bank ready for the movement of its wipers in a vertical plane due to the final series of impulses to be presently received from the subscriber's instrument. After the last impulse just described by which the primary magnet PM' is operated, the relay IR' remains energized as before. Magnet M being differentially wound again releases its armatures thereby opening the circuit at the 105 armature 43 and closing the circuit at the 110 armature 45, thereby establishing a circuit through the relay SW which may be traced from ground through battery, through said relay, through contact spring 46, conductor 47^a, contacts of the secondary off normal 115 switching mechanism SON' by way of armature 45 to ground through the switch contact 39 of the primary off normal switching mechanism PON'. Relay SW is thus energized and locks itself by way of the 120 armature 47 to ground through the switch arm 39. By the operation of this relay SW the circuit through the primary magnet PM' is broken at the armature 44 and established to the secondary magnet SM'. At 125 the same time the circuit from the private wiper 47^b is broken at the armature 48. The subscriber now sends his second series of impulses for the connector to actuate its 130 wipers in a vertical plane. The relay IR'

responds as before and the relay M is actuated the same as before. The secondary magnet SM' thus has its circuit completed through the armatures 44, 43 and 41 to the 5 ground at 42, whereby the wipers are advanced the correct number of steps to engage the wipers 49 and 50 with the line wires 51 and 52 of the desired line. The first step of course moves the secondary off 10 normal switching device SON' to its alternative position. After the last impulse, relay M is again deenergized. Relay SW' is thereupon energized, circuit for which extends from the ground by way of armature 15 45, armature 53, through relay SW', through battery to ground, it being noted that the secondary off normal switch SON' is in its alternative position to thereby ground the armature 45. Operation of the relay SW' 20 opens the circuit of the relay SW at the armature 47, whereupon said relay SW restores its armature 53, switching the circuit of the said relay SW' to the armature 54 of the reversing relay RV, in multiple with the 25 relay MRR' and closing the private circuit at the armature 48 of the relay SW. The circuit to the called substation C is thus completed and the only relays which bridge the talking circuit are the relays SR' and 30 IR'.

It will be noted that the relay IR' supplies the talking current to the calling station and the relay SR' supplies the current to the called station. Now if the subscriber 35 called for is busy, then the wiper 47^b will find a ground on the multiple contact of this line whereby relay SW' will be held up to control the connection of the busy buzz BB' on the line of the calling subscriber. 40 The calling subscriber thereupon hangs up. Whereupon the relay IR' is deenergized to ground the back contact of the armature 32, thereby establishing a circuit from this ground by way of armature 36 of the relay 45 SR' through the right hand winding of the relay RR', whereby this relay releases to close the circuit of the interrupter INT by way of the primary off normal switch PON' through the secondary magnet SM' whereby 50 the connector completes the movement of its wipers in a vertical plane whereupon said connector rotates and then drops back to its normal position, thus operating the primary off normal contacts PONG and secondary off normal contacts SON' to withdraw the ground connection. Thereupon the first selector releases as it is held up merely by the ground connection of the connector and this releasing operation continues in the reverse order of the setting up 55 operation. If the called for party is not busy, then the wiper 47^b does not find a ground, whereupon the relay SW' is deenergized closing the circuit of the private 60 wiper 47^b by way of armature 48 by way of

the relay RI to ground at the armature 34. Relay RI thereupon operates as the wiper 47^b has found battery through the cut-off relay CO', whereby this relay RI short circuits its previously energized winding and establishes a circuit through its other winding, also grounding the private wiper 47^b by way of the armature 34. The relay RI thereby connects the ringing generator G to the contacts of the relay CD and connects the interrupter INT through the winding of said relay CD. The relay CD thereupon intermittently causes a ringing current to be transmitted to the substation C. If the party at the substation C answers relay SR' is actuated to actuate the relay RV through the grounded armature 55. The reversing relay RV thus reverses the connection of the relay IR' with the lines of the calling subscriber as well understood, 85 and through the agency of the armature 54 also operates the relay MRR' to disconnect the generator G and the interrupter INT'. Relay MRR' locks itself through the ground by way of the armature 54 so that if the 90 called subscriber vibrates his switchhook, relay RV is actuated, which reverses the battery on the line for toll supervision as well understood. When both subscribers hang up the release operation is the same as 95 when the calling subscriber hangs up if unable to raise the called subscriber.

An important feature of my invention concerns itself also primarily with preventing the called subscriber from holding up 100 the entire connection in case the calling subscriber hangs up, but the called subscriber does not. Assuming that the calling subscriber hangs up, relay IR' releases to break the circuit of the relay M at the armature 105 41. This circuit however is made again at the armature 32 by way of the closed contact on the relay SR' at the armature 36 so that relay M pulls up and immediately restores, but during this interval between 110 the operation of the two armatures 41 and 32 has opened the circuit of the wire 25 leading to the second selector or first selector as the case may be, thereby releasing this first selector. When the armatures of 115 the relay M restore however, the busy test is again placed upon the wire 25 by way of the armature 56 of said relay M. Everything thus releases but the connector. If the called party then hangs up, relay SR' 120 is deenergized, whereupon the right hand winding of the relay RR' receives its quota of current by way of the armatures 35, 36 and 32, thus releasing said relay RR' and causing a release of the connector.

From what has been described the nature of my invention will be clear as will also its application to this as well as other systems.

Having however thus described one form which my invention may take, what I claim is

as new and desire to secure by Letters Patent is:

1. In an automatic telephone exchange system the combination with a plurality of switches adapted to be set up in a series to establish a connection, means controlled by a calling subscriber's line to set said switches to complete a connection to a called line, and means controlled at the calling station operable after response of a called connected station to release the connection of said calling station from said called station independently of said connected called station, said last aforesaid means including a circuit controlling element adapted to be rapidly moved from one position to its alternative position and back again to thereby momentarily release the holding circuit for the other switches of the series.
  2. In an automatic telephone exchange system the combination with a plurality of switches adapted to be set up in a series to establish a connection, means controlled by a calling subscriber's line to set said switches to complete a connection to a called line, and means controlled at the calling station operable after response of a called connected station to release the connection of said calling station from said called station independently of said connected called station, said last aforesaid means including a circuit controlling element adapted to be rapidly moved from one position to its alternative position and back again to thereby momentarily release the holding circuit for the other switches of the series, and by its second movement to restore the ground connection to the terminal of said holding circuit.
  3. In an automatic telephone exchange system the combination with a plurality of switches adapted to be set up in a series to establish a connection, means controlled by a calling subscriber's line to set said switches to complete a connection to a called line, and means controlled at the calling station operable after response of a called connected station to release the connection of said calling station from said called station independently of said connected called station, said last aforesaid means including a circuit controlling element adapted to be rapidly moved from one position to its alternative position and back again to thereby momentarily release the holding circuit for the other switches of the series, and by its second movement to restore the ground connection to the terminal of said holding circuit, and a relay for operating said circuit controlling element.
  4. In an automatic telephone exchange system the combination with a plurality of switches adapted to be set up in a series to establish a connection, means controlled by a calling subscriber's line to set said switches to complete a connection to a called line, and means controlled at the calling station operable after response of a called connected station to release the connection of said calling station from said called station independently of said connected called station, said last aforesaid means including a circuit controlling element adapted to be rapidly moved from one position to its alternative position and back again to thereby momentarily release the holding circuit for the other switches of the series, and by its second movement to restore the ground connection to the terminal of said holding circuit, and a relay for operating said circuit controlling element.
- means controlled at the calling station operable after response of a called connected station to release the connection of said calling station from said called station independently of said connected called station, said last aforesaid means including a circuit controlling element adapted to be rapidly moved from one position to its alternative position and back again to thereby momentarily release the holding circuit for the other switches of the series, and by its second movement to restore the ground connection to the terminal of said holding circuit, and a relay for operating said circuit controlling element, and a second relay controlled directly by the called line having means to effect the rapid dual action of said first aforesaid relay.
5. A metallic line control circuit for automatic switches comprising an impulse relay, a two conductor operating circuit for said relay having a call transmitter connected therewith, means for rapidly operating the impulse relay responsive to said call transmitter for transmitting primary impulses, a differential release relay having an initial operating winding responsive to the initial energization of the impulse relay to attract its armature, means for holding said armature attracted during the primary operations of the impulse relay, a neutralizing winding for said release relay effective to cause a retraction of its armature only responsive to an extended deenergization of the impulse relay, and a relay to control the connection of said impulse relay with said control circuit.
6. A metallic line control circuit for two dimension automatic switches including an impulse relay, a two conductor operating circuit for said relay having a call transmitter connected therewith, means for rapidly operating the impulse relay responsive to said call transmitter for transmitting primary impulses, a differential secondary relay operated over one of its windings to attract its armature responsive to the first primary operation of the impulse relay, a neutralizing winding for said secondary relay effective upon cessation of the primary operations of the impulse relay to cause a secondary circuit change following the primary impulses, and a circuit and connections for said secondary differential relay independent of said two conductor operating circuit.
7. A telephone system including a telephone line, a two-dimension automatic switch for extending connection from said telephone line, an impulse relay for said switch responsive to circuit changes in said telephone line, a differential secondary relay responsive to said impulse relay for controlling a secondary circuit, a switching relay for disconnecting said impulse relay from the said telephone line, and means con-

- trolled by said switching relay for releasing the said automatic switch.
8. In a telephone system a subscriber's line, an automatic switch for extending a connection from said line having a primary motion to select groups of lines and a secondary motion to select an idle line in a group, an impulse relay for controlling said primary motion, a differential secondary relay controllable by said impulse relay for controlling the second of said motions, and a switching relay for disconnecting the said impulse relay after said switch has been operated to connect to an idle one of said lines.
9. A telephone system including a subscriber's line, an automatic switch adapted to be connected to said line, an impulse relay for said switch responsive to circuit changes in said subscriber's line, a differential relay for said switch for effecting a secondary circuit change, a third relay for disconnecting said impulse relay from said subscriber's line, and a release circuit for said switch adapted to be effected when said last relay is deenergized.
10. In a telephone system a subscriber's line, an automatic switch adapted to be connected to said line, an impulse relay for said switch responsive to circuit changes in said subscriber's line, a differential secondary relay controllable by said impulse relay for effecting a secondary circuit change, a switching relay for disconnecting said impulse relay from said subscriber's line after said secondary relay has been operated, and means for subsequently operating said last relay to bring about a release of said switch.
11. A telephone system including a subscriber's line, an automatic switch adapted to be connected to said subscriber's line, an impulse relay for said switch responsive to circuit changes in said telephone line, a differentially wound release relay responsive to a prolonged deenergization of said impulse relay, and a switching relay for disconnecting said impulse relay from said subscriber's line and for rendering ineffective the operations of said release relay.
12. A telephone system including a subscriber's telephone line, an automatic switch adapted to be connected to said telephone line, an impulse relay responsive to circuit changes in the said telephone line, a release relay for controlling a release circuit, said release relay being responsive to a prolonged deenergization of said impulse relay, and a switching relay for disconnecting said im-
- pulse relay whereby said impulse relay is deenergized and said release relay rendered ineffective to release said automatic switch.
13. A telephone system comprising a subscriber's telephone line, an automatic switch for extending a connection from said line having one motion for electing groups of trunk lines and a second motion for selecting an idle trunk in the elected group of trunk lines, an impulse relay for controlling said first motion, a differential secondary relay for controlling the said second motion, and a third relay for disconnecting said impulse relay after said switch has been operated to select an idle trunk.
14. A telephone system comprising a subscriber's line, an automatic switch for extending a connection therefrom, an impulse relay for said switch adapted to be bridged across the subscriber's line circuit, means for operating said impulse relay for transmitting primary impulses, a differential secondary relay, means for operating said secondary relay upon the cessation of said primary impulses to effect a secondary circuit change, a switching relay adapted to subsequently disconnect said impulse relay from said subscriber's line, and means for returning said switch to normal.
15. An automatic switch of the character described for extending connections, an impulse relay for said switch controllable over the two sides of a calling subscriber's line in series, a differential secondary relay responsive to an operation of said impulse relay to effect a secondary circuit change, a differentially wound release relay responsive to a prolonged deenergization of said impulse relay, and a switching relay for disconnecting said impulse relay from the subscriber's line thereby removing the subscriber's control of said impulse relay and said differential relays.
16. A line control circuit for an automatic switch comprising an impulse relay, means for operating said impulse relay to transmit impulses, differentially wound secondary and release relays for said switch, and a switching relay for disconnecting said impulse relay control circuit.
